CLAIM

I claim the ornamental design for a tray support railing, as shown and described.

DESCRIPTION

FIG. 1 is a front perspective view of the tray support railing.

FIG. 2 is a front elevation view thereof.

FIG. 3 is a top plan view thereof.

FIG. 4 is a left side elevation view thereof.

FIG. 5 is a right side elevation view thereof.

FIG. 6 is a rear elevation view thereof.

FIG. 7 is a bottom plan view thereof; and,

FIG. 8 is a bottom perspective view thereof.
